UNITED STATES PATENT OFFICE

JAYSON K. BOND, OF MILWAUKEE, WISCONSIN

CIRCULATORY SYSTEM FOR REFRIGERATED COUNTERS

Application filed February 28, 1929. Serial No. 343,356.

This invention relates to improvements in circulatory systems for refrigerated counters.

This invention relates to improvements in circulatory systems for refrigerated counters.

It is one of the objects of the present invention to provide a refrigerated counter in which the misting or deposits of moisture on the front glass is eliminated whereby vision into the counter or case is not obstructed.

A further object of the invention is to provide a refrigerated display counter or cooler having a circulating system of such a character that moisture laden air from the room, which enters when the counter door is opened, is carried directly to the cooling coils before it can come into contact with the cold glass front of the counter, whereby condensation is minimized.

A further object of the invention is to provide a refrigerated counter in which the moving air, with a capacity for moisture, does not come into direct contact with the counter contents, whereby meats or perishables therein are not dried out or dehydrated.

A further object of the invention is to provide a refrigerated display counter of the class described in which the counter contents are entirely surrounded by, but not in contact with, cold air in motion.

A further object of the invention is to provide a refrigerated display counter of the class described in which the air is caused to move upwardly the full height of the front vision glass of the case and said air will absorb any moisture which might be on the glass.

A further object of the invention is to provide a circulatory system for refrigerated counters which is very simple in construction, is efficient, and is well adapted for the purposes described.

With the above and other objects in view the invention consists of the improved circulatory system for refrigerated counters or

coolers, and its parts and combinations as set forth in the claims, and all equivalents thereof.

In the accompanying drawings in which the same reference characters indicate the same parts in all of the views:

Fig. 1 is a cross-sectional view of a refrigerated display counter or cooler illustrating the improved circulatory system therefor;

Fig. 2 is a vertical longitudinal sectional view taken on line 2—2 of Fig. 1;

Fig. 3 is a cross-sectional view illustrating the circulatory system applied to a modified form of counter or case; and

Fig. 4 is a vertical longitudinal sectional view taken on line 4—4 of Fig. 3.

Referring to the drawings and particularly to Figs. 1 and 2 thereof, it will appear that the numeral 8 indicates a refrigerated display counter or cooler which is mounted on supporting legs 9. The counter has a slightly forwardly inclined insulated bottom 10, an angularly extending glazed front portion 11, slideable entrance doors 12 forming an upper rear portion, an insulated lower rear portion 13, and a top portion 14. Within the counter, inwardly of the lower rear portion 13 is an enclosed compartment 15 in which is a longitudinally extending coil 16 for the purpose of cooling the interior of the counter.

Extending across the width of the bottom portion 10 of the counter, and longitudinally of the same, is a tray 17 supported above said bottom portion by spaced-apart transverse legs 18. The front edge portion of said tray is formed with a longitudinal row of spaced apertures 19 for the passage of air therethrough and immediately rearwardly of said apertures is a low vertical baffle wall 22. The rear portion of said tray is formed with a vertical wall 20 closing the front of the coil compartment 15 and said wall is secured at its upper edge to an upper rail 21 of said compartment.

The lower end portions of a plurality of

spaced-apart angularly, upwardly extending flues or chimneys 23 open through said wall 20 into the upper front portion of the coil compartment 15. Said flues extend parallel with the rear doors 12, inwardly of the same, and the open upper end portions of the flues terminate below an upper light compartment 24, and are joined by an elongated, longitudinally extending trough 25, of angular shape in cross-section, and which abuts at its inner edge against a top rail 26, preventing flow of air behind the trough.

It will thus be seen that in the counter the coil compartment is entirely closed except for the entrance at the upper front portion by the several flues 23 and at the lower front portion an exit is formed to the ducts between the tray 17 and insulated bottom 10. The result of this arrangement is that air is cooled by the coils in the compartment 15 and naturally falls and is also pushed downwardly by the column of air thereabove and then travels forwardly in the slightly inclined duct below the tray. The cooled air may then escape through the openings 19 in the forward portion of the tray and travels upwardly, as it becomes warmer, along the full height of the front glass 11 to the top of the counter. Here the air is arrested by the trough 25 and is carried therealong to the open upper ends of the flues 23 where suction, caused by downwardly moving air in the flues and compartment 15, draws the air downwardly in the flues to the coil compartment to be again cooled.

Obviously, as shown by the arrows in Fig. 1, the direction of circulation is downwardly from the coils in an inclosed space, and then forwardly at a slight downward angle to the front of the counter, and then upwardly in proximity to the glass to the trough and then downwardly to the coils. When the counter entrance doors are opened there is a rush of warm air into the upper portion of the case. This air, being warm, will rise and is arrested by the current in the trough and very little, consequently, reaches the front glass to mist the same. Hence, moisture laden air from the room is quickly carried to the coils and condensation is minimized. If, however, warm air does reach the front glass, due to the doors being left open too long, it is quickly picked up by the air current therealong.

55 A further advantage of the counter circulatory system lies in the fact that the circulation is around, but not in direct contact with, meat or perishables on the tray, whereby dehydrating is eliminated.

60 In Figs. 3 and 4 of the drawings the invention has been illustrated in connection with a counter having a lower storage compartment 27 in addition to the upper display compartment 28. The lower portion of this counter has insulated end and front walls 29 and 30,

70 rear doors 31 and an insulated bottom 32. The compartment 27 is separated from the compartment 28 by the tray 17 resting on spaced longitudinal rails 33. The bottom portion of the coil compartment 15 opens into the upper rear portion of the compartment 27 through a passage-way 34 and the air circulation is as clearly indicated in Fig. 3.

75 From the foregoing description it will be seen that the improved circulatory system for refrigerated display counters or coolers is simple, novel and efficient, and is well adapted for the purposes described.

What is claimed as the invention is:

1. In a refrigerated display counter, an angular duct therewithin and opening into the interior of the counter at its lower forward portion, a cooling medium within a portion of said duct, a pair of separated flues entering said duct remote from its open end portion and extending upwardly within said counter, and a trough connecting the upper portions of said flues.

2. In a refrigerated display counter having a display compartment, a rear enclosed refrigerant chamber, a tray forming the bottom portion of said display compartment and having a rear vertical wall closing the front of said refrigerant chamber, said chamber being open below the tray and the front end portion of the tray having an air discharge opening, a pair of separated flues extending from an upper portion of said display compartment along the rear thereof and opening into said refrigerant chamber above the discharge end portion of said tray, the upper end portions of said flues being open, and a trough connecting the open upper end portions of said flues.

3. In a refrigerated display counter, a cooling chamber along the rear thereof and a substantial distance below the upper portion of said counter, said chamber being entirely enclosed but having an upper inlet opening and a lower outlet opening, a cold fluid duct extending forwardly within said counter from said outlet opening, the forward end portion of said duct having an outlet opening, and a downwardly, rearwardly directed fluid conductor within the rear portion of said counter and entering said chamber inlet opening, the outer end portion of said conductor having an opening therein relatively close to the top of the counter.

4. In a refrigerated display counter having a display compartment, a rear enclosed refrigerant chamber, a slightly forwardly inclined tray having front outlet openings and extending longitudinally of the counter and forming the bottom portion of said display compartment, the rear edge portion of said tray meeting the front enclosing wall of the refrigerant chamber, said enclosing wall having a pair of spaced upper inlet openings and a lower outlet opening to discharge fluid be-

low said tray, a pair of separated downwardly directed fluid conductors within the rear portion of said counter and entering said chamber inlet openings, the outer end portions of said conductors being open, and a longitudinally extending trough within the upper rear portion of the display compartment and joining the open upper end portions of said conductors.

10 In testimony whereof I affix my signature.
